[57] **CLAIM**

The ornamental design for a watercraft with hull, center hydroplane and wing, substantially as shown and described.

DESCRIPTION

FIG. 1 is a port side view of the watercraft with the outboard motor shown in dotted lines. The starboard side is like the port side.

FIG. 2 is a frontal view of the watercraft of FIG. 1;

FIG. 3 is a top view of the watercraft of FIG. 1;

FIG. 4 is a bottom view of the watercraft of FIG. 1;

FIG. 5 is a rear view of the watercraft of FIG. 1.
The dotted lines shown in the several views are disclosed for illustrative purposes only and form no part of the claim.
